GOVERNOR MECHANISM FOR AUTOMATIC TRAIN CONTROL

Filed Feb. 23, 1923

2 Sheets-Sheet 2

UNITED STATES PATENT OFFICE.

WILLIAM M. BECK, OF ELWOOD, INDIANA.

GOVERNOR MECHANISM FOR AUTOMATIC TRAIN CONTROL.

Application filed February 23, 1923. Serial No. 620,745.

To all whom it may concern:

Be it known that I, WILLIAM M. BECK, a citizen of the United States, residing at Elwood, in the county of Madison and State of Indiana, have invented new and useful Improvements in Governor Mechanism for Automatic Train Control, of which the following is a specification.

This invention relates to train devices for preventing wrecks on railways caused by open switches, or collisions caused by one or more trains disregarding block or other signals, or failing to stop at the proper place.

A principal object here sought to be accomplished is to provide such an automatic stopping device as is above referred to, with means whereby a train may pass an automatic stop in stopping position without the brakes of the train being applied or the power shut off, provided the speed of the train is less than a predetermined number of miles per hour.

Another object is to record the number of times that the automatic stopping device has been applied to stop a train, and also to provide means requiring the stopping device to be re-set by a person who must be off of the train during any re-setting operation, thereby to insure proper inspection of the cause of the automatic stopping of the train.

The object also is to provide an automatic stopping device that will not interfere with the normal control of the motive power by the driver, and that cannot be operated manually from the engine or car, or in any other way than automatically as same was primarily intended to be operated.

I accomplish the above, and other objects which will hereinafter appear, by the mechanism illustrated in the accompanying drawings, in which—

Fig. 1, is a side elevation of a locomotive engine shown largely in dotted lines, to which my invention is operatively applied and shown in full lines in position about to contact a track device and automatically set the brakes and shut off the power. Fig. 2, is a vertical longitudinal section, on a larger scale, of the cylinder and piston mechanism for operating the throttle lever of a locomotive and showing said throttle lever in perspective. Fig. 3, is a longitudinal horizontal section of the mechanism shown in

Fig. 2. Fig. 4, is a vertical section of the right hand side of a locomotive engine, on the line 4—4 of Fig. 1, showing my invention on a larger scale than Fig. 1 and showing parts broken away to bring the illustration within the compass of the sheet. Fig. 5, is a front view of the air-valve and trip mechanism shown in Fig. 4. Fig. 6, is a modified form of my device as applied to an electrically propelled car. Fig. 7, is a portion in vertical section on the line 7—7 of Fig. 6, and Fig. 8, is a portion in vertical section on the line 8—8 of Fig. 4.

Like characters of reference indicate like parts in the several views of the drawings.

Referring in detail to the drawings, 9 represents a locomotive engine of any suitable or well known construction, in which 10 is the brake-valve having a hand-lever 11 by which it is normally manipulated by the engine driver. This valve is connected with the air-line of the train by a pipe 12, with which I connect a branch pipe 13 that communicates with the interior of a cylinder 14. A valve 15 controls communication between the pipes 12 and 13, and in open position allows air under pressure to fill the cylinder 14. In cylinder 14 is a reciprocating piston 16 which is forced to the front end of the cylinder by air pressure from pipe 13. Small holes 17 in the front end of the cylinder permit the air in the cylinder ahead of the piston to escape gradually; and the brakes of the train with which the train-pipe 12 is connected are correspondingly set in a gradual manner which is desirable. A piston rod 18 connected with the piston has a loop 19 on its outside portion through which a throttle-lever 20 is assembled. The lever 20 connects in the usual manner not shown with the steam supply to the driving cylinders of the locomotive, and as the brakes are set in the manner above described the driving power of the locomotive is cut off.

The loop 19 has a top cam-face 21 near its outer end, which raises an elongated pin 22 pivoting a rod 23 of pawl 24 to a hand-lever 25, and thereby lifts the pawl out of the notches of a segment 26 releasing the throttle-lever which is then moved by the continued forward travel of the piston.

The cylinder 14 has a vent-cock 27 at its rear end and a valve 28, operated by a lever

29 and a rod 30, the latter extending within reach of the driver in the cab, all for convenience in re-setting the piston.

I will now describe the automatic opening of the valve 15, which, in the manner above stated, sets the brakes of the train and cuts off the power. The immediate control of said valve is by a lever 31 which is moved normally in a direction to open the valve, 5 by a spring 32, connecting the end of the lever with the frame 33 of the locomotive. The lever is swung down against the tension of the spring 32 to closed position of the valve and is there held by the engagement 10 of a bracket 34 on the lever with a roller 35, carried by a trip-bar 36. The pin of the roller passes through a longitudinal slot 37 in the trip-bar which retains the roller with free vertical adjustment. This is limited 15 in downward direction by the pivoted bracket 34 and in upward direction by a horizontal foot-extension from the end of a bracket 38, which bracket 38 is bolted rigidly to the engine frame 33. The roller is 20 thus held in a relatively fixed position while the trip-bar 36 is free to move longitudinally within the limits of said slot. The roller-contacting ends of the bracket and the foot between which said roller is held, are 25 concaved to better retain the roller and will retain it except under the stress of an appreciable force against the trip-bar, which swings bracket 34 on pivot 31 to miss bracket 38.

30 The trip-bar is hinged at 40, to swing parallel with the railroad track 41, and its lower end is adapted to contact a track device 42 located in the path of the trip-bar, which contact forces the roller out of the 35 grip of the brackets 34 and 38 and immediately releases the lever 31 so that the lever 31 moving under the stress of spring 32 opens the valve 15. A friction-roller 43 is 40 preferably mounted in the lower end of the trip-bar to contact the track device 42, for 45 obvious reasons.

A counter of any suitable and well known construction is mounted at the hinge joint 40, and a pin from the counter to operate its 50 mechanism is held between and engaged by a pair of pins carried by the lower trip-bar member, whereby the number of movements of the trip-bar and consequent number of 55 emergency train stops is registered on the counter.

It will be noted that no means is provided 60 for re-setting the mechanism for holding lever 31 in closed position of valve 15 from the engine-cab or train. This mechanism can purposely only be re-set by a person 65 standing on the ground, which is desirable because it insures that the trainmen get off the train to ascertain the occasion of the non-scheduled stop.

65 It is important, however, for low speed

in switching and the like, that the train be not stopped by said automatic stop mechanism, and I provide for this contingency by a governor control that raises the trip-bar 70 out of possible contact with the track device below a predetermined speed of the train.

The governor 44 is of usual construction and operation and is here shown as located in the cab of the locomotive, but that will depend upon circumstances and requirements. It is operatively connected with a lever 45 to which the upper end of the trip-bar is pivoted. The speed of the governor is controlled by connection with the axle 46 of one pair of the track-wheels of a locomotive, here shown as the rear drive wheels, but that is optional. A splined shaft 47 has a sliding drive through the correspondingly shaped hub of a bevel wheel 48, and it is connected by a universal joint 49 with a bevel wheel 50 drivingly engaging the bevel wheel on the axle. This allows for variations between the axle and engine frame 33, from which frame the wheel 48 is supported by means of a suitable bracket. A shaft 51 90 is connected by a pair of bevel wheels with an upwardly extending shaft 52 that drives a cog-wheel 53 which in turn drives a cog-wheel on the governor shaft. The shaft 52, as here shown, has two universal joints but 95 a greater or less number may be used depending upon the obstructions which it may be necessary to avoid in the various types of locomotives to which my invention is applied.

100 In the modification shown in Fig. 7, the governor control is applied to an electrically driven railway car such as is in common use on urban and interurban roads. The governor is here located low and in front of the motorman but it may be otherwise placed in any desirable and suitable place, and instead of drivingly connecting it with the axle of the car by means of shafting provided with universal joints and sliding shaft 105 as in Fig. 1, I have shown a flexible drive shaft 50 of usual and well known construction for transmitting power from suitable bevel gear wheels 51 and 52' at the axle to similar bevel gear wheels 53' and 54 at the 110 governor shaft. A trip-bar substantially like that shown in Fig. 1, and connected with the governor-shaft by mechanism similar to that shown in Fig. 1, holds a like valve-lever 31 in closed position of an air-valve by a like roller and roller holding means. In this modification direct air pressure is used for setting the car brakes. Compressed air from a suitable source of supply (not shown) is supplied through a pipe 115 55 and is discharged through a pipe 56 to the brake mechanism (not shown). The discharge from pipe 55 to pipe 56 is through a valve-controlled connection normally 120 opened by a manually operated hand-lever 125 130

57 at the motorman's station. But I have shown them as connected under the car by an additional pipe connection 58 in which there is a valve 59 to which the lever 31 is attached (see Fig. 8) and when the valve is opened by the lowering of the lever 31 compressed air passes from the pipe 55 to the pipe 56 through the connecting pipe 58 to set the brakes. The automatic air system 10 shown in Fig. 1 may be used instead of the direct air system shown in Fig. 7 if so desired or if that is the equipment of the particular car to which my invention is applied.

The lever 31 has an extension 69 on the 15 opposite side of the valve 59, which extension rests upon a handle 60 of a double knife switch 61 of usual construction, in the motor-circuit. The raising of the lever 31 by spring 32 when the lever is released by the 20 swing of the trip-bar causes the extension 69 to open the switch thereby breaking the circuit to the motor and discontinuing the motive power of the car.

The handle 60 swings down by gravity 25 into locking engagement with a spring-catch 62 where it remains until normally released for the re-setting of the safety device, which, as before stated, is done manually.

The operation of my invention is so obvious from the detailed description already given that further description of its operation is unnecessary.

While I have here shown the best form of my invention now known to me, it is obvious 35 that many changes can be made without departing from the spirit of the invention, some of which I have herein described, and I therefore do not desire to be limited to the precise forms shown nor any more than 40 is required by the appended claims; and having thus fully described my invention what I claim as new and wish to secure by Letters Patent of the United States, is—

1. In an apparatus for the purposes 45 specified, a track device, in combination with a train device, said train device comprising a trip member having a jointed portion moved at certain positions of the bar by contact with the track device, a rotating governor 50 nor located in view of the operator at his station, means including automatic universal adjustment to avoid interference by train movement for rotating the governor at variable speeds correspondingly varying with 55 the speed of the train, and means operated by the governor for raising the trip member out of possible contact with the track device at all speeds of the train below a predetermined speed thereof.

60 2. In an apparatus for the purposes specified, the combination of a track device with a train device, said train device comprising an axle, a trip member having a jointed portion moved at certain positions 65 of the bar by contact with the track device,

a centrifugally acting rotary governor in view of and accessible to the operator, means having automatic universal adjustment for rotating the governor from the axle and means connecting the governor and trip 70 member for raising the trip member out of possible contact with the track device below a predetermined speed of the governor.

3. In an apparatus for the purposes specified, the combination of a track device 75 with a train device, said train device comprising an axle, a trip-bar having a hinged portion adapted to be swung at certain positions of the bar by contact with the track device, a centrifugally rotary governor, 80 means for rotating the governor from the axle, joints in said last means permitting universal translatory adjustment, a pivoted lever connected with the trip-bar and a governor shaft connected with and oscillating the lever by the centrifugal action of the governor whereby the trip-bar is raised out of possible contact with the track device at a train speed below a predetermined speed. 85

4. In an apparatus for the purposes specified, a track member, a trip member carried by the train and moved by contact with the track member, a counting device, 90 means operated by the movement of the trip member for actuating the counting member and automatic means for moving the trip member out of possible contact with the track member below a predetermined speed of the train. 95

5. In an apparatus for the purposes specified, a track member, a trip-bar carried by the train and having a hinged section which is swingingly moved by contact with the track member, a counter located adjacent to the hinge, and means on the swinging member of the trip-bar cooperating with the counter mechanism for registering and counting each swinging movement of the trip-bar and automatic means for raising the trip-bar to miss the track member and avoid movement of the counter below a predetermined speed of the train. 100

6. In an apparatus for the purposes specified, a train device comprising a pipe connected with the air-brake system of the train, a valve regulating the air discharge from said pipe, a lever connected with said valve to open and close it by the swinging of the lever, spring means for normally holding the lever in open position of the valve, a trip-bar automatically adjustable longitudinally with the speed of the train and having a hinged and swingable lower portion, means for locking the valve-lever 115 in a position of closure of the valve, and means by a swinging movement of the hinged end of the trip-bar for releasing said valve-lever. 120

7. In a device for the purposes specified, 130

2
a track device, a pipe connected with a pneumatic brake system for cars, a valve opening and closing said pipe, a lever controlling the valve, means for actuating the lever toward open position of the valve, means for locking the lever against the action of said first means, in closed position of the valve, and a longitudinally movable trip-bar having a lower pivoted member 5 which is swingingly moved by contact of the member with the track-device to unlock the lever.

8. In a device for the purposes specified, a track device, a pipe connected with a pneumatic brake system for cars, a valve opening and closing said pipe, a lever controlling the valve, a locking member on the lever, means for actuating the lever toward open position of the valve, a trip-bar, and 15 means comprising a member carried by the trip-bar and interlocking with the locking member on the lever for holding the lever in closed position of the valve until released by a movement of the trip-bar caused by 20 contact of said bar with the track device.

9. In a device for the purposes specified, a track device, a pipe connected with a pneumatic brake system for cars, a valve opening and closing said pipe, a lever controlling the valve, a bracket on the lever, a bracket supported in a relatively fixed position adjacent the first bracket, a trip-bar, a member carried by the trip-bar and held 25 between the two brackets until released by contact of the trip-bar with the track device.

10. In a device for the purposes specified, a track device, a pipe connected with a pneumatic brake system for cars, a valve opening and closing said pipe, a lever controlling the valve, a bracket pivoted to the lever, a spring acting on the lever and closing the valve, a trip-device having a longitudinal slot, a shaft adjustably mounted in the slot and extending above the bracket 40 on the lever and holding the lever against the action of its spring, and means to impinge the shaft against the bracket on the lever and holding the lever until the shaft is released by contact of the trip-bar with 45 the track device.

11. In an apparatus for the purposes specified, a track device, a pipe connected with a pneumatic brake system for cars, a valve opening and closing said pipe, a spring closing the valve in one position of the lever, a pivoted trip-bar, means carried by the trip-bar for holding the lever in closed position to the valve, and means allowing for free adjustment of the first 55 means longitudinally of the trip-bar without releasing the valve-lever until the trip-bar is swung on its pivot by contact with the track device.

12. In an apparatus for the purposes specified, a track device, in combination

with a train device, said train device comprising a trip-bar, a rotating governor, means for rotating the governor at variable speeds correspondingly varying with the speed of the train, a pipe connected with a pneumatic brake system for cars, a valve opening and closing said pipe, a lever controlling the valve, a bracket on the lever, a bracket supported in relatively fixed position adjacent to the first bracket, a member carried by the trip-bar and held between the two brackets until released by contact of the trip-bar with the track device.

13. In an apparatus for the purposes specified, a track device, a train device comprising a pipe connected with the air-brake system of the train, a valve regulating the air discharge from said pipe, a lever connected with said valve to open and close it by the swinging of the lever, spring means for normally holding the lever in open position of the valve, a trip-bar having a hinged and swinging lower portion, means for locking the valve-lever in a position of closure of the valve, means by a swinging movement of the hinged end of the trip-bar for releasing said valve-lever, a rotating ball-governor located at the driver's station, means for rotating the governor at speeds varying with the speed of the train, and means operated by the governor for raising the trip-bar out of possible contact with the track member below a predetermined speed of the train.

14. In an apparatus for the purposes specified, the combination of a track device with a train device, said train device comprising an axle, a ball-governor located at the driver's station, a flexible shaft-drive from the axle to the governor, a pivoted lever connected with the governor, a trip-bar connected with the lever the lower portion of the trip-bar being hinged to the upper portion, a pipe connected with a pneumatic brake system for cars, a valve opening and closing the pipe, a lever controlling the valve, a spring acting on the lever to close the valve, interlocking means between the last devices and the lower portion of the trip-bar automatically adjustable longitudinally of the trip-bar and having means for releasing the valve-lever by a swinging movement of the lower member caused by contact with the track device.

15. In an apparatus for the purposes specified, the combination of a track device with a train device, said train device comprising an axle, a ball-governor located at the driver's station, a flexible shaft-drive from the axle to the governor, a pivoted lever connected with the governor, a trip-bar connected with the lever the lower portion of said trip-bar being hinged to the upper portion thereof, and said lower portion having a longitudinal slot, a pipe con-

nected with a pneumatic brake-system for cars, a valve opening and closing the pipe, a downwardly bent lever controlling the valve, a spring moving the lever to close the valve, a lateral member adjustably held in the slot of the trip-bar, means for locking the valve-lever to the lateral member and for unlocking it by a movement of the trip-bar about its pivot, and means from the frame of the engine for supporting said locking means.

Signed at Indianapolis, Indiana, this the 17th day of February, 1923.

WILLIAM M. BECK.
